ATTORNEYS.

UNITED STATES PATENT OFFICE.

EMIL M. KRUEGER, OF MILWAUKEE, WISCONSIN, ASSIGNOR TO BADGER METER MANUFACTURING COMPANY, OF MILWAUKEE, WISCONSIN.

WATER-METER CASING.

Application filed February 4, 1924. Serial No. 690,481.

To all whom it may concern:

Be it known that I, EMIL M. KRUEGER, a citizen of the United States, residing at Milwaukee, county of Milwaukee, and State of 5 Wisconsin, have invented new and useful Improvements in Water-Meter Casings, of which the following is a specification.

My invention relates to improvements in water meter casings. Water meters are 10 quite frequently exposed to low temperatures and if the water therein freezes, the outer casings are often broken. These casings constitute one of the most expensive parts of 15 the meter and if broken, or distorted, they must be replaced. Even when not frozen the casing is sometimes distorted by unequal pressure, such as results from an improper attachment of the bottom plate, if the casing is constructed in accordance with the 20 prevailing practice heretofore followed.

The objects of my invention are to provide a meter casing which will not be destroyed if the liquid contents become frozen; which will not be distorted by an unequal tightening of the clamping bolts; in which the bolts will be protected against corrosion; in which water of condensation will drain away freely without dripping upon screw threaded parts; in which the bolts are received in 25 lugs which project outwardly from the casing wall and constitute reenforcing trusses for said wall in combination with a circular flange at the lower margin of the wall, whereby maximum strength is secured in 30 proportion to the material used, and whereby the tendency toward distortion under the tension of the clamping bolts is reduced to a minimum.

A further object of my invention is to 35 provide a bottom clamping plate having apertured arms to receive the clamping bolts and with the extremity of the arm enlarged downwardly and adapted to receive the pressure of the bolt heads or washer members 40 at points exterior to the opening in the main casing.

In the drawings:

Figure 1 is a side elevation of a meter casing embodying my invention.

Figure 2 is a view of the same in reverse and partly in vertical section, drawn generally to a central plane cutting the inlet port.

Figure 3 is a view of the casing as seen

from the underside, with the bottom plate and supported mechanism removed. 55

Figure 4 is a sectional view of the bottom plate in inverted position.

Figure 5 is a view of the bottom plate as seen from the underside.

Like parts are identified by the same reference characters throughout the several views.

The body of the casing has a substantially cylindrical wall 1, a spherically rounded portion 2, neck portion 3, and head portion 65 4,—the latter containing the registering wheels and dial. The water actuated mechanism is mounted within the cylindrical portion 1 and this portion is provided with the usual inlet stud 6 and outlet stud 7. If desired, the wall 1 may be slightly enlarged, 70 conically, in a downward direction.

The cylindrical portion 1 is provided at spaced intervals with radially projecting abutments or lugs 8 which preferably have 75 tapering upper end portions 9. These abutments are each arranged in the form of a buttress or truss to support the wall of the casing. The base of each of these lugs rests upon, and forms a part of, an outwardly extending base flange 10 which, being formed integrally with the cylindrical wall 1 and with the lugs 8 and the tapering extensions 9, forms a structure of great strength and 80 rigidity. The abutments are arranged in 85 diametrically opposite pairs and, with the spherically rounded portion 2, constitute, in effect, trusses in the form of an inverted U.

The lugs 8 have threaded sockets extending upwardly therein and closed at their 90 upper ends. These sockets receive the cap screws 11 which connect the bottom plate or cap 12 with the casing. The flange 10 and the lugs 8 overhang these screws and protect them from water which otherwise 95 would collect upon the screw threads and cause rapid corrosion.

The bottom plate 12 is provided with radially projecting arms 13 having apertures 14 through which the screws 11 pass. 100 The extremities of these arms are thickened on the underside, as indicated at 15 in Figures 4 and 5, and these thickened portions receive the clamping pressure of the heads of the screws or bolts. Each of these heads 105 comprises a wrench receiving portion 17 and

a washer-shaped portion 18. The outer half of the latter bears upon the thickened portions 15 of the arms 13 when the screws or bolts are adjusted to clamping position, and therefore the clamping pressure is primarily applied to the extreme outer ends of the arms 13. The material of which these arms is composed will yield slightly if excessive pressure is applied to one of the screws or bolts—i. e.—if the bolts are not uniformly adjusted into clamping relation with the plate.

The upper surface of the plate has a central concave portion 20 encircled by a flange 21 and the water actuated mechanism is supported within this concave portion of the plate. The flange 21 bears against an annular shoulder 23 formed at the lower end of the casing wall 1 on the interior side and a gasket 25 may be interposed between said shoulder and the flange 21 to make a water tight joint.

With the above described construction, the meter casing will not be broken or distorted if the water therein becomes frozen. The spherically rounded portion 2 will receive the pressure in such a manner as to develop a tendency to force the contents of the casing downwardly. The radial pressure will be resisted by the abutments 8 and the flange 10 and this resistance will be much greater than that of the bottom plate or that of its radial arms 13. Therefore, before the wall of the casing body has been broken or distorted, the arms 13 will break and release the bottom bolt. The resistance of the spherically rounded portion 2 of the body wall will be such that the mass of frozen material will expand downwardly and thus break any adhesion at the sides, or any anchorage in the passageways of the inlet and outlet ports. Therefore, when the bottom breaks, the tendency of the expanding material will be to push downwardly through the bottom opening and the pressure upon the wall 1 may be substantially wholly relieved if its interior surface is conically enlarged to a slight extent in the downward direction. It will of course be understood that the spherically rounded portion 2 protects the neck portion 3 and head portion 4 from upward pressures. The water cavity of the meter does not extend to the neck and head portion. This will be apparent from an inspection of Figure 2.

The body wall 1 is provided on its interior surface with shoulders 28 between which a screen 29 may be loosely fitted. This screen covers the inlet port 6 and it may be readily replaced when replacing a broken bottom plate. The outlet port extends through a reenforcing rib 30 which extends upwardly along the interior surface of the wall 1.

By employing washer-shaped members 18

on the screw or bolt heads 17, the necessity for supplying loose washers is eliminated and the application of the clamping pressure directly to the portions 15 of the arms 13 is assured. The arms 13 will break before the bolt or screw threads will strip or distort. Therefore, the screws or bolts may be readily removed when the bottom plate becomes broken, since the engaged portions of the threads are protected against corrosion from the point of initial engagement to the extreme upper ends of these screws or bolts. If grease or equivalent material is applied to the threads before they are screwed in place, it will remain and resist corrosion indefinitely for the reason that it is not exposed to external influence.

I claim:

1. A meter casing having a water receiving cavity provided with a spherically rounded top wall, and a substantially cylindrical side wall provided with an outwardly extending peripheral base flange and flanked by exterior lugs extending upwardly along the side wall from the base flange, and having threaded bolt receiving sockets closed at their upper ends and adapted to receive clamping bolts from beneath.

2. A meter casing comprising the combination of a body portion having a water receiving cavity provided with an outwardly extending peripheral base flange and flanked by exterior diametrically opposite pairs of lugs extending upwardly from the base flange along the wall of the body and integrally connected with said flange and body wall, a detachable bottom plate provided with radially extending apertured arms, and clamping bolts extending through the apertures of said arms and having threaded engagement in said lugs, said lugs having threaded sockets closed at their upper ends and adapted to receive said bolts.

3. A meter casing comprising the combination of a body portion having a water receiving cavity provided with an outwardly extending base flange and flanked by exterior diametrically opposite pairs of lugs extending upwardly from the base flange along the wall of the body and integrally connected with said flange and body wall, a detachable bottom plate provided with radially extending apertured arms, clamping bolts extending through the apertures of said arms and having threaded engagement in said lugs, said lugs having threaded sockets closed at their upper ends and adapted to receive said bolts, and the arms of said base plate being thickened at their outer ends and adapted to receive the clamping pressure of the bolt heads exterior to the axial centers of the bolts.

4. A meter casing comprising the combination of a body portion provided with a water receiving cavity, an exterior periph-

eral base flange, and a spherically rounded top portion; said body also having integral exterior lugs extending upwardly from the base flange and adapted to resist expanding pressures against the side walls of the body, a bottom plate adapted to close the lower end of the body and provided with radially extended apertured arms of minimum strength intermediate their ends, clamping bolts extending through the apertures of said arms and socketed in said lugs at points exterior to the wall of the body, said clamping bolts being engaged with their respective base plate arms near the outer extremities of said arms and beyond their zones of greatest weakness.

5 5. A meter casing comprising the combination of a body portion provided with a water receiving cavity, an exterior peripheral base flange, and a spherically rounded top portion; said body also having integral exterior lugs extending upwardly from the base flange and adapted to resist expanding pressures against the side walls of the body, 10 a bottom plate adapted to close the lower end of the body and provided with radially extended apertured arms of minimum strength intermediate their ends, clamping bolts extending through the apertures of said 15 arms and socketed in said lugs at points exterior to the wall of the body, said clamping bolts being engaged with their respective base plate arms near the outer extremities of said arms and beyond their zones of greatest 20 weakness, said arms having their extremities enlarged downwardly and said bolt heads having washer-shaped portions of which the parts radially remote from the center of said bottom plate bear against the 25

enlarged portions of the arms and exert 40 their clamping pressure at points beyond the body wall of the casing.

6. A meter casing having a cup-shaped body opening toward its bottom and provided at peripherally spaced points about said opening with radially projecting lugs, said body being formed integrally to provide buttresses connected with said lugs and tapering upwardly therefrom, whereby exteriorly to truss said body, and a bottom plate 45 50 clamped to the said lugs.

7. A meter casing comprising unitarily a cup-shaped body adapted to house the working parts of a meter and provided with a spherically rounded inner end, and a series 55 of buttresses projecting radially from said body, said buttresses being formed to merge with said body adjacent the rounded end thereof and to extend with increasing radial projection and size toward the opposite end of said body, whereby exteriorly to truss said body and increasingly to re-enforce said body at points remote from its spherically rounded end.

8. A meter casing comprising a tubular 60 wall integrally provided with a dome-shaped head and with an open end encircled by a peripheral flange, radially projecting lugs 65 formed integrally with said wall and said flange and provided with downwardly opening screw holes, said lugs being upwardly tapered toward the wall of said casing adjacent said dome-shaped head, whereby said lugs and said flange co-operate with said head to comprise a truss structure for re-enforcing said tubular wall.

EMIL M. KRUEGER.
